The ornamental design for a beverage brewer, as shown and described.

DESCRIPTION

FIG. 1 is a front right perspective view of a beverage brewer; FIG. 2 is a front left perspective view thereof; FIG. 3 is a rear left perspective view thereof; FIG. 4 is a front view thereof.

FIG. 5 is a left side view thereof; FIG. 6 is a right side view thereof; FIG. 7 is a rear view thereof; and, FIG. 8 is a top view thereof.

The broken lines show portions of the beverage brewer and form no part of the claimed design.
